WIRING TROUGH

Leonard Atkin, Springfield, N. J., assignor to Stone Manufacturing Co., a corporation of New Jersey

Application March 15, 1956, Serial No. 40,633

Term of patent 14 years

(Cl. D26—1)

FIG. 1.

FIG. 2.

FIG. 3.

FIG. 4.

FIG. 5.

Figure 1 is a front elevational view of a wiring trough showing my new design;

Figure 2 is a view similar to Figure 1 showing the cover plate removed;

Figure 3 is a rear elevational view thereof;

Figure 4 is a top view thereof; and

Figure 5 is an end view thereof.

I claim:

The ornamental design for a wiring trough, substantially as shown.
